ATTORNEY.

UNITED STATES PATENT OFFICE.

CHRISTIAN B. KYLE, OF PHILADELPHIA, PENNSYLVANIA.

DEFLECTOR FOR HEADLIGHTS.

Application filed September 22, 1920. Serial No. 411,986.

To all whom it may concern:

Be it known that I, CHRISTIAN B. KYLE, a citizen of the United States, residing at Philadelphia, county of Philadelphia, and 5 State of Pennsylvania, have invented a new and useful Improvement in Deflectors for Headlights, of which the following is a full, clear, and exact description, reference being had to the accompanying drawings, which 10 form a part of this specification.

This invention relates to lights for vehicles, and more particularly to headlights for automobiles, and is designed to provide an efficient shield or deflector for a lamp in 15 the focal center of a parabolic reflector, which will prevent the intense rays of light from being projected above a given plane, and at the same time intensify the light 20 thrown on the road directly in front of the car.

A further object of my invention is to provide a shield or deflector, which can readily be inserted between the lamp in the focal center of a parabolic reflector and a dimmer 25 lamp out of focus, and which can be rigidly secured in position in headlights now in use without changing their construction.

The precise nature of my invention will be best understood by reference to the accompanying drawings, which will now be described, it being premised, however, that changes may be made in the details of construction without departing from the spirit and scope of my invention, as defined in the 35 appended claim.

Fig. 1 is a front view of one form of reflector with my invention applied thereto.

Fig. 2 is a vertical section through Fig. 1, with a lamp in the focal center, and a 40 lamp out of the focal center.

Fig. 3 is a face view of a removable deflector.

Fig. 4 is a perspective view of the device shown in Fig. 3.

In Figs. 1 and 2 of the drawings the reference character 2 designates a parabolic reflector having an annular flange 3. 4 are key slot openings in the flange for securing the reflector in a lamp casing in the well 50 known manner.

The reflector is provided with two lamp openings 5 and 6 for the reception of lamps 7 and 8, respectively, the lamp 7 being in the focal center of the reflector while the lamp 55 8 is above the focal center.

Mounted in the reflector between the two lamps is a deflector 9 whose surface is of crescent shape and is bent to form a segment of a parabola.

The deflector is secured along its peripheral edge to the reflector 2 by soldering or in any other desired manner, but is so mounted that its concaved surface is next to the lamp in the focal center, so that the deflected rays of light above a given plane will 60 be reflected back to the reflector 2 from which they will be again reflected below the outer edge of the deflector, to the road directly in front of the car, so that the light at this portion will be increased, while the 65 objectionable light rays from the focused lamp above a predetermined plane will be eliminated.

In Figs. 3 and 4 I have shown a deflector similar to that shown in Figs. 1 and 2, but 70 in which the deflector is formed integrally with a supporting ring, and which is adapted to be inserted in a reflector such as shown in Figs. 1 and 2, and secured in position by means of the reflector securing means, without soldering the deflector to the reflector.

In this form 3^a designates a ring having key slot openings 4^a therein, and 9^a the deflector which is integral with an arcuate shaped strip 10 extending from one side of 85 the ring to the other side. 11 designates a tab secured to the deflector 9^a at approximately the center of its peripheral edge, and which is provided with an opening 12 for the reception of the plug of the lamp in the 90 focal center of the reflector.

This form may be made by first blanking out the device and then shaping the deflector between dies.

The device shown in Figs. 3 and 4 is arranged to be secured in reflectors already on the market, or may be used in connection with new lamps, so that the deflector can readily be removed if desired. When securing this device in position the key slot 95 holes 4^a are engaged with the usual reflector securing devices, and the plug of the lamp in the focal center is then inserted through the opening 12 into the socket or opening in the center of the reflector, so that the deflector 100 will be retained in position by the reflector retaining members and the lamp in the focal center.

The advantages of my invention result from the provision of a deflector of para- 110

bolic form for a parabolic reflector which is arranged to deflect and reflect the rays of light from a focused lamp above a predetermined plane, back to the parabolic reflector by which they are reflected to a lower plane to increase the light on the road in front of the vehicle or automobile.

Having now fully described my invention, what I claim and desire to protect by Letters Patent is:—

A removable deflector for a parabolic reflector comprising a continuous annular supporting frame, a crescent shaped deflector bent into the form of a segment of a para-

bola, the outer periphery of the deflector being arranged to contact with the face of the reflector, an arcuate shaped supporting member formed integrally with and extending from one side of the frame to the other side to which the inner periphery of the deflector is connected, means for securing the annular frame against the flange of the reflector, and other means for supporting the deflector by the lamp.

In testimony of which invention, I have hereunto set my hand, at Philadelphia, Pa., on this 17th day of September, 1920.

CHRISTIAN B. KYLE.
